FOREIGN PATENT DOCUMENTS

GB 2233269 A 1/1991

Primary Examiner — Philip S Hyder*(74) Attorney, Agent, or Firm* — DINSMORE & SHOHL LLP(57) **CLAIM**

The ornamental design for a punch with orientation feature, as shown and described.

DESCRIPTION

FIG. 1 is a first perspective view of a first embodiment of a punch with orientation feature in accordance with the present invention;

FIG. 2 is a second perspective view of the punch with orientation feature of FIG. 1 from a different direction;

FIG. 3 is a first end view of the punch with orientation feature of FIGS. 1 and 2;

FIG. 4 is a second end view of the punch with orientation feature of FIGS. 1-3;

FIG. 5 is a first side view of the punch with orientation feature of FIGS. 1-4;

FIG. 6 is a second opposite side view of the punch with orientation feature of FIGS. 1-5;

FIG. 7 is top view of the punch with orientation feature of FIGS. 1-6;

(Continued)

FIG. 8 is a bottom view of the punch with orientation feature of FIGS. 1-7;
FIG. 9 is a first perspective view of a second embodiment of a punch with orientation feature in accordance with the present invention;
FIG. 10 is a second perspective view of the punch with orientation feature of FIG. 9 from a different direction;
FIG. 11 is a first end view of the punch with orientation feature of FIGS. 9 and 10;
FIG. 12 is a second end view of the punch with orientation feature of FIGS. 9-11;
FIG. 13 is a first side view of the punch with orientation feature of FIGS. 9-12;
FIG. 14 is a second opposite side view of the punch with orientation feature of FIGS. 9-13;
FIG. 15 is top view of the punch with orientation feature of FIGS. 9-14;
FIG. 16 is a bottom view of the punch with orientation feature of FIGS. 9-15;
FIG. 17 is a first perspective view of a third embodiment of a punch with orientation feature in accordance with the present invention;
FIG. 18 is a second perspective view of the punch with orientation feature of FIG. 17 from a different direction;
FIG. 19 is a first end view of the punch with orientation feature of FIGS. 17 and 18;
FIG. 20 is a second end view of the punch with orientation feature of FIGS. 17-19;

FIG. 21 is a first side view of the punch with orientation feature of FIGS. 17-20;
FIG. 22 is a second opposite side view of the punch with orientation feature of FIGS. 17-21;
FIG. 23 is top view of the punch with orientation feature of FIGS. 17-22;
FIG. 24 is a bottom view of the punch with orientation feature of FIGS. 17-23;
FIG. 25 is a first perspective view of a fourth embodiment of a punch with orientation feature in accordance with the present invention;
FIG. 26 is a second perspective view of the punch with orientation feature of FIG. 25 from a different direction;
FIG. 27 is a first end view of the punch with orientation feature of FIGS. 25 and 26;
FIG. 28 is a second end view of the punch with orientation feature of FIGS. 25-27;
FIG. 29 is a first side view of the punch with orientation feature of FIGS. 25-28;
FIG. 30 is a second opposite side view of the punch with orientation feature of FIGS. 25-29;
FIG. 31 is top view of the punch with orientation feature of FIGS. 25-30; and,
FIG. 32 is a bottom view of the punch with orientation feature of FIGS. 25-31.
The broken lines are directed to unclaimed subject matter and are for illustrative purposes only; the broken lines form no part of the claimed design.
